UNITED STATES PATENT OFFICE.

JERVIS R. HARBECK, OF CHICAGO, ILLINOIS, ASSIGNOR TO AMERICAN CAN COMPANY,
OF NEW YORK, N. Y., A CORPORATION OF NEW JERSEY.

FOOD-DISPENSING DEVICE.

1,194,172.

Specification of Letters Patent. Patented Aug. 8, 1916.

Application filed August 1, 1912. Serial No. 712,648.

To all whom it may concern:

Be it known that I, JERVIS R. HARBECK, a citizen of the United States, residing in Chicago, in the county of Cook and State 5 of Illinois, have invented a new and useful Improvement in Food-Dispensing Devices, of which the following is a specification.

This invention relates to an improvement in means for handling and dispensing food, 10 such as crackers, and the invention consists in the novel parts and devices and combinations thereof hereinafter described and made the subject matter of claim.

In the accompanying drawing which 15 forms a part of this specification, Figure 1 is a perspective view of the dispensing apparatus. Fig. 2 is a perspective view of the containing, shipping and charging cartridge, shown as it is before it is placed in 20 the outer case. Fig. 3 is a vertical, sectional view, at the point indicated by 3—3 in Fig. 1, the lid of the box, however, being shown as closed in said Fig. 3, instead of open, as in Fig. 1. Fig. 4 is a horizontal 25 section of the same on the line 4—4 of said figure. Fig. 5 is a section of a fragment of one of the walls of the inner package or sealed cracker containing cartridge.

In the handling and sale of bakery products of various kinds, such as crackers, biscuit, pretzels, cakes, etc., it has long been customary for the baker to furnish the grocer or retail dealer with a sheet metal box having a hinged lid and a glass front panel, 30 in which box or case the crackers to be sold are placed and displayed by the merchant, and from which they are dispensed in required quantities to the consumer. Sometimes these sheet metal display and dispensing 35 cases have been used for containing the crackers during shipment. Naturally, it has been found that such sheet metal display and dispensing boxes, after considerable use, have become not merely tarnished, 40 but foul and unsanitary by reason of the crumbs that are left in its interior, and especially so in moist and humid atmospheres and climates. This has necessitated the frequent shipment of such sheet metal 45 cases back to the baker for cleansing, 50 burnishing, etc. It is the purpose of the present invention to provide such dispensing boxes with a sanitary, protective lining to preserve the crackers from contact with the 55 interior of said sheet metal boxes. At the

same time, this protective lining is so constructed and contrived that it may serve as a sealed container or vessel in which the crackers may be sealed up and preserved for any length of time from all access of 60 moisture or deleterious conditions, and in which the crackers may be safely shipped by the baker to the merchant, and at the same time so contrived or constructed that the merchant may cause the crackers in the 65 container to be visible through the glass front of the sheet metal dispensing box. The said sealed containers may be shipped to the merchant, kept by him for any length of time and then charged into the sheet 70 metal dispensing box as a cartridge is inserted in a gun, and the seal being then broken, the contents of the package may be dispensed in the usual manner from the sheet metal dispensing box with the difference that said box is now lined. It is one 75 of the purposes of this invention to make this cracker containing cartridge of a cheap material, preferably of paper so prepared as to be moisture proof, which is preferably 80 done by making the walls of this paper container of two layers of paper joined together by a fused cement. The upper surface of this cartridge and one of its walls is marked with a guide marking so that the 85 paper may be cut out to open the side at a point opposite the glass window of the dispensing box and to open the top of the cartridge for access to the crackers contained 90 therein, and it is preferred that some automatic device, such as a tearing string may be had to facilitate such cutting.

In the said drawing, A is a dispensing box, made preferably of sheet metal provided with a hinged cover a, and having the 95 glass front window B. Similar boxes are in extensive use, and such may be adapted for the purposes of this invention; but since the ordinary dispensing box is provided with an inwardly projecting, strengthening 100 band at the top, which would somewhat interfere with the introduction of a full sized cartridge, I prefer to construct the sheet metal box, especially for this purpose, with no inward projections, but fitted to receive smoothly a full sized cartridge adapted to fill the box completely, and such a dispensing box is shown in the drawings. The removable cartridge protective lining or 105 shipping package C, shown at Fig. 2, is 110

made of the same general shape as the interior of the dispensing package, and preferably of a size to exactly fit the same. I make this package of paper or fiber board, 5 employing two thicknesses joined together by an adhesive, fused cement, so that the walls shall be impervious to moisture, air, grease or any deleterious substance. The crackers are placed within this package and 10 sealed up hermetically in any well known manner. They are thus placed in condition to be kept for any reasonable length of time without deterioration, since no moisture can have access to them, and in this condition 15 they may be shipped into any climate by simply inclosing the package or a number of such packages in an ordinary protective crate or box. The best practice in shipping such packages to a new customer, will be 20 to crate several of the packages together, inclosing one of the several crated packages in a sheet metal display box of the kind above described, the display box in such case taking up no extra room in the shipment 25 and adding little or nothing to the cost of the shipment, beyond the cost of the display box itself.

To facilitate the handling of the cartridges and the dispensing of their contents, 30 the top of the cartridge is marked with a tearing or cutting line D, which may serve as a guide for removing the panel D¹ or portion of the top, to give access to the crackers in the package in dispensing the 35 same. A folding handle D², secured to the panel D¹, is a convenience for lifting the panel out after it is cut, and for lifting the package itself before the panel is cut. This handle is shown raised up in Fig. 2, and 40 folded down in Fig. 1. The front of the package is also marked with a tearing or scoring line E, conforming in position, and preferably also in extent to the glass window in the sheet metal dispensing box, and 45 to facilitate the removal of a panel or por-

tion E¹, to render the contents of the package visible through the glass window of the dispensing box when the cartridge shall have been inserted therein. As a means of easily cutting out the marked portions or 50 panels D¹ and E¹, a tearing string F may be employed. This tearing string is threaded through the perforations f. It will be readily understood that if the end of the string F is taken hold of and pulled, the 55 paper wall will be torn along the marked line by pulling of the string through the paper until a corner is reached, when the tearing is continued at right angles, and so on around the rectangle to the starting 60 point, the corners being left intact to be subsequently cut out with a knife or pulled out by a forcible removal of the panel.

The final end of the tearing string should be secured to the paper in some manner, 65 either by a large knot or by gumming or gluing the string to the paper. In case the perforations are larger than the string, it is better also to fill the perforations with gum or to paste or gum a small strip of paper 70 (not shown) over these holes on the outside.

I claim:-

The combination with the sheet metal display box having a window through which its contents may be seen, of the loose, 75 interior fitting, sealed food containing package made of paper rendered moisture proof, said interior package having one of its walls marked for cutting to conform to the window in the sheet metal box, and provided 80 with means for performing the cutting act, consisting of a string threaded in the paper at the corners of the opening so as to perform such cutting in a continuous straight line along each side of the opening, substan- 85 tially as specified.

JERVIS R. HARBLECK.
